(No Model.)

C. C. LOCKSTAEDT.
RECLINING CHAIR.

No. 477,906.

Patented June 28, 1892.

UNITED STATES PATENT OFFICE.

CHARLES C. LOCKSTAEDT, OF CHICAGO, ILLINOIS.

RECLINING-CHAIR.

SPECIFICATION forming part of Letters Patent No. 477,906, dated June 28, 1892.

Application filed December 18, 1891. Serial No. 415,455. (No model.)

To all whom it may concern:

Be it known that I, CHARLES C. LOCKSTAEDT, a subject of the Emperor of Germany, residing at Chicago, in the county of Cook 5 and State of Illinois, have invented certain new and useful Improvements in Reclining-Chairs; and I do hereby declare the following to be a full, clear, and exact description of the invention, such as will enable others skilled in the art to which it appertains to make and use the same.

This invention relates to a novel construction in reclining-chairs, the objects being to provide a device of this character of simple, 15 durable, and inexpensive construction.

The invention consists in the features of construction and combination of parts hereinafter fully described and claimed.

In the accompanying drawings, illustrating 20 my invention, Figure 1 is a side elevation, partly in section, of a chair constructed in accordance with my invention. Fig. 2 is a similar view showing the chair in another position. Fig. 3 is a detail view.

Referring to said drawings, A indicates the base, and B the seat of the chair, which can be of ordinary construction.

C indicates the back of the chair, which is pivoted to the rear edge of the seat, and D 30 indicates the leg-piece pivoted to the front edge of the seat in a familiar manner.

To each side of the seat B is pivoted a lever 1. The upper ends of said levers 1 are pivoted to the arms 2 of the chair, and said 35 arms 2 are pivoted at their rear ends to the back C. The lower ends of the levers 1 are pivotally connected with the ends of links or bars 3, and the said bars 3 are pivoted at their other ends to the leg-piece D. It will be noted 40 that the back, arms, and leg-piece are connected together, and therefore must move in unison, so that a person occupying the chair when in an erect position needs only to move the leg-piece slightly, as described hereinafter, 45 and then to move his body backwardly and the back of the chair will conform to such movement, while the leg-piece will rise, as shown in Fig. 2. As soon as the pressure upon the back of the chair ceases the back 50 and leg-piece become stationary and will re-

main so until power is applied to move them. In this way it will be noted the chair can be brought to any position between an erect and prone to suit the fancy or inclination of the occupant and will always remain in the de- 55 sired position.

It will be noted that the links and leg-piece form, in effect, a toggle-joint between the levers 1 and forward edge of seat B, so that when the back C is erect the knuckle of said 60 toggle-joint will stand in alignment with the pivots of the ends of the toggle-joints, or to the other side of said pivots, and thus lock the chair in its erect position. It will be noted in this connection that by constructing 65 the parts so that the knuckle of the toggle-joint stands in alignment with or a little to the other side of the pivots of the toggle when the leg-piece is thrown back said leg-piece will be locked when it is moved into this po- 70 sition. In Fig. 3 of the drawings I have clearly shown such parts constructed so that the knuckle of the toggle passes slightly to the other side of the pivots of the toggle; but it will be understood that in accordance with 75 the idea embraced by my invention the same results would be obtained if the knuckle and pivots of the toggle-joint were constructed so as to be located in alignment with each other when the back is erect and said leg-piece 80 thrown back, because then the back could not be moved without first moving the leg-piece to bring the knuckle to the other side of the said pivots of the toggle. When the back C is to be thrown back, it will be necessary to 85 move the leg-piece forward to bring the knuckle of the toggle-joint to the other side of said pivots in an obvious manner. A foot-piece 4 is provided with side arms 5, pivoted to the sides of the leg-piece, and stop-pins 6 90 limit the outward swing of said foot-piece.

I claim as my invention—

A chair comprising a base, a seat supported thereby, a back hinged to the rear of the seat, arms pivotally connected to the back, levers 95 pivotally connected to the arms and to the seat, a leg-rest having pivotal connection with the seat, and links pivotally connected to the levers and to the leg-rest, the said pivotal connection of the link with the leg-rest being 100

in alignment with or to one side of the pivotal connection of the leg-rest to the base and the link when the back is in its normal position, whereby the leg-rest and the back are secured against movement when these parts are in such normal position, substantially as described.

In testimony whereof I affix my signature in presence of two witnesses.

CHARLES C. LOCKSTAEDT.
